(57) **CLAIM**

The ornamental design for a bin external sign holder, as shown and described.

DESCRIPTION

FIG. 1 is a front perspective view showing our new design for a bin external sign holder;

FIG. 2 is a front perspective view thereof;

FIG. 3 is a rear perspective view thereof;

FIG. 4 is a front view thereof;

FIG. 5 is a rear view thereof;

FIG. 6 is a top view thereof;

FIG. 7 is a bottom view thereof;

FIG. 8 is left side view thereof; and,

FIG. 9 is right side view thereof.

The broken lines shown in the figures represent portions of the bin external sign holder that form no part of the claimed design.
